vale, Pa., a corporation of Pennsylvania

Application July 5, 1941, Serial No. 401,185

15 Claims. (Cl. 188—62)

My invention relates to railway braking apparatus, and particularly to car retarders for use in freight classification yards for controlling the speed of cars.

One object of my invention is to provide means for automatically moving the braking bars of a car retarder to their open or non-braking positions when locomotives having wide wheels approach the retarder to prevent the possibility of derailment of a locomotive and damage to the retarder resulting from a locomotive inadvertently passing through the retarder while the braking bars are in their closed or braking positions.

According to my invention, I provide a relay which is arranged to be picked up, when a locomotive having wide wheels approaches the retarder in either direction, over a control circuit which is controlled by rail contactors so constructed and so arranged that they will be operated when and only when a wide car wheel passes them. This relay when picked up completes a stick circuit which subsequently holds the relay picked up if the control lever for the retarder then occupies any position but its "off" position, and at the same time modifies the control circuits for the retarder in a manner to cause the retarder to automatically move the braking bars to their open positions. If desired, a warning signal may be provided to inform the lever operator that the retarder is being automatically moved to its open position, whereby the operator is informed that the retarder occupies a position in disagreement with the position of the control lever. The control of the retarder by the lever can be restored by returning the lever to its "off" position which causes the relay to become deenergized. The contactors are located far enough from the ends of the retarder so that there is sufficient time for the retarder to open before a locomotive traveling at the ordinary yard speeds approaches it.

Other objects and characteristic features of my invention will become apparent as the description proceeds.

I shall describe one form of apparatus embodying my invention, and shall then point out the novel features thereof in claims.

In the accompanying drawings, Fig. 1 is a view partly diagrammatic and partly cross sectioned illustrating one form of apparatus embodying my invention. Fig. 2 is an end view of a rail contactor forming part of the apparatus illustrated diagrammatically in Fig. 1. Fig. 3 is a top plan view of a portion of the rail contactor illustrated

in Fig. 2. Fig. 4 is a diagrammatic view illustrating one location and arrangement of track rail contactors which may be employed in connection with a retarder which is positioned directly in front of a switch. Fig. 5 is a view of a contactor operating structure operable from either of two tracks.

Similar reference characters refer to similar parts in each of the several views.

Referring to the drawings, the reference character 1 designates one track rail of a stretch of railway track, which track rail, as here shown, is secured to a rail support 2 mounted on an adjacent pair of the usual crossties 3, only one crosstie being visible in the drawings. Associated with the rail 1 is a car retarder comprising two braking bars A1 and A2 located on opposite sides of rail 1. Each of these braking bars comprises, as usual, a brake beam 4 and a brake shoe 5.

20 The braking bars A1 and A2 are arranged to be moved toward and away from the rail 1 through the medium of a lever 6 which is pivotally mounted at one end on a pivot pin 8 carried by the rail support 2, and a lever 7 which is pivotally mounted intermediate its ends on the pivot pin 8. The lever 6 is inclined upwardly and extends away from the rail 1 and is provided in its upper surface with a groove 6a which receives the braking bar A1. The one end 7a of

25 the lever 7 is likewise inclined upwardly and extends away from the rail 1 at the opposite side of the rail from the lever 6, and the other end 7b of the lever 7 is inclined downwardly and extends away from the rail 1 below the lever 6.

30 The end 7a of the lever 7 is provided in its upper surface with a groove 7c, similar to the groove 6a in the lever 6, which groove receives the braking bar A2. The parts are so arranged and so proportioned that if the outer or free ends of the levers 6 and 7 are moved apart, the braking bars will be moved toward the rail into their effective or braking positions. When the braking bars

35 will engage their braking positions, the brake shoes will occupy the opposite side faces of a car wheel traversing the rail 1 and will thus retard the speed of the car. The center of gravity of the lever 6 and braking bar A1 is considerably to the left of the pivot pin 8 so that this lever will

40 normally tend to rotate in a counterclockwise direction about the pivot pin. Similarly, the center of gravity of the lever 7 and braking bar A2 is to the right of the pivot pin 8 so that this lever will normally tend to rotate in a clockwise direction about the pivot pin. It will be apparent, therefore, that when no force is applied

to the ends of the levers 6 and 7 to move them apart, the free ends of these levers will move toward each other, thereby moving the braking bars to their ineffective or non-braking positions in which they are illustrated in the drawings.

The levers 6 and 7 are arranged to be moved apart by means of a fluid pressure motor M comprising a cylinder 9 containing a reciprocable piston 10 which is attached to the inner end of a piston rod 11. The cylinder 9 is pivotally connected with the free ends of the lever 6 by means of trunnions 12 formed on the side of the cylinder and extending through bifurcations 13 formed on the lever 6 while the piston rod 11 is connected at its free end with the free end 7b of the lever 7 by means of an adjustable eyebolt 14 and a pivot pin 15. Fluid pressure may be admitted to the cylinder 9 between the upper end of the cylinder and the piston 10 through an opening 16 which is threaded to receive a pipe 17. When fluid pressure is admitted to the cylinder 9 through the pipe 17 and opening 16, the piston 10 will be forced downwardly and the cylinder 9 upwardly, thereby separating the levers 6 and 7, and hence moving the braking bars toward their effective or braking positions. It will be obvious that when the braking bars are moved to their braking positions, they will exert a braking force which is proportional to the pressure of the fluid supplied to the cylinder 9.

The motor M is controlled by two magnet valves V1 and V2, each comprising a valve stem 18 biased to an upper position by means of a spring 19, and provided with a winding 20 and an armature 21. When valve V1 is energized, valve stem 18 of this valve moves downwardly against the bias exerted by the associated spring 19, and pipe 17 is then connected with atmosphere through a port 22. When valve V1 is de-energized, however, pipe 17 is disconnected from atmosphere. When valve V2 is energized, valve stem 18 of this valve moves downwardly, and connects the pipe 17 through a pipe 23 with a pipe 24 which is constantly supplied with fluid pressure, usually air, from a suitable source not shown in the drawing, but when valve V2 is de-energized, as shown in the drawing, pipe 23 is disconnected from the pipe 24. It will be apparent, therefore, that when valve V1 is energized, the region of cylinder 9 of motor M between the piston 10 and the upper end of the cylinder is connected with atmosphere, so that the braking bars of the car retarder will then be held in their ineffective or non-braking positions by gravity. When, however, valve V1 is de-energized and valve V2 is energized, fluid pressure will be supplied to the upper end of cylinder 9 of motor M thus causing the braking bars to move to their effective or braking positions.

The valves V are controlled in part by a plurality of pressure responsive devices P20-30, P45-55, and P70-80, each comprising a Bourdon tube 25 connected to the pipe 17, and hence subjected to the pressure of the fluid in the region of cylinder 9 between piston 10 and the upper end of the cylinder. Each Bourdon tube 25 controls two contacts 26-26a and 26-26b. The pressure responsive devices P20-30, P45-55, and P70-80, are so constructed and so adjusted that they will operate successively as the pressure in the region of cylinder 9 between the piston 10 and the upper end of the cylinder increases. For example, for all pressures below 20 pounds per square inch, the contact 26-26a of each of these devices is closed. If the pressure exceeds 20

pounds per square inch, however, contact 26-26a of device P20-30 opens, and if the pressure exceeds 30 pounds per square inch, contact 26-26b of device P20-30 closes. In similar manner, the pressure responsive devices P45-55 and P70-80 are adjusted to open their contacts 26-26a at 45 and 70 pounds per square inch, respectively, and to close their contacts 26-26b at 55 and 80 pounds per square inch, respectively. Of course, these specific pressures are not essential but are only mentioned for purposes of explanation.

The valves V are controlled by means of a manually operable lever L which as here shown is capable of assuming five positions, indicated by dotted lines in the drawing and designated by the reference characters p1 to p5, inclusive. The lever L controls a plurality of contacts each designated by the reference character 27 with a distinguishing suffix corresponding to the position of the lever in which the corresponding contact is closed. For example, contact 27-1 is closed in the p1 position of the lever, contact 27-2 in the p2 position of the lever, etc.

Lever L will usually be located at a point remote from the braking apparatus, as in the control cabin of a classification yard car retarder system, and will be connected with the braking apparatus by means of line wires extending from the control cabin to the braking apparatus.

The valves V are also controlled in part by a relay D which relay, in turn, is controlled by two rail contactors RC1 and RC2 and by the lever L. The contactors RC1 and RC2 are located respectively in advance and in rear of the retarder, and may have any desired construction which will cause an associated contact to become closed when and only when locomotives having wide wheels pass the contactors. As here shown, these contactors are each similar to the contactor shown in detail in Figs. 2 and 3.

Referring to Figs. 2 and 3, the contactor here illustrated comprises a vertical lever 61 provided at its upper end with a contact shoe 60, and at its lower end with a channel shaped recess 62 which loosely receives the base flange of the rail 1 in such manner that the lever is free to pivot about the base flange as a fulcrum. Pivotally attached to the lever intermediate its ends by means of a pivot pin 63 is a spring bolt 64, the free end of which extends with clearance through a hole 65 in the rail web and is provided with a compressed spring 66, a thrust washer 67, and a spring tension adjusting nut 68. The spring 66 serves to bias the lever toward the rail 1 to a position in which a screw 69 adjustably screwed through the upper end of the lever engages the side of the head of the rail, and this screw is so adjusted that car wheels of the usual width will clear the contact shoe, but that, the wide wheels of locomotives will engage the contact shoe and will rotate the lever in a counterclockwise direction as viewed in Fig. 2 about its point of engagement with the base flange of the rail.

The lever 61 is also connected by means of a connecting rod 70 to the operating crank of a circuit controller 71. This circuit controller may be of any suitable type, but as here shown this circuit controller is similar to that shown and described in Letters Patent of the United States No. 2,199,520, granted to Edwin G. Little on February 13, 1940. For purposes of my present disclosure it is sufficient to point out that this circuit controller includes a contact 72 shown diagrammatically in Fig. 1, which contact is open when the lever 61 occupies its normal position in

which it is illustrated in the drawing, but which contact becomes closed when the lever is rotated away from its normal position by the wide wheels of a locomotive.

In many cases, car retarders are located directly in front of a switch in the manner shown diagrammatically in Fig. 4, and when this condition exists, it is necessary to provide a contactor on each track in rear of the switch to permit the contactors to be spaced far enough away from the retarder, for a reason which will appear presently. When it is desired to provide a contactor on each track, the spring rod 65 of the contactor associated with the track rail 1 of the one track may be connected by means of a turn-buckle 73 and a connecting rod 74 with another lever 61a similar to the lever 61, which latter lever is associated with one of the track rails 1a of the other track. With this arrangement, a locomotive approaching the retarder from the right, as viewed in Fig. 4, on either track will actuate the circuit controller through the medium of the lever 61 or 61a associated with that particular track, and this arrangement has the advantage that it requires only one circuit controller for both tracks.

It should be particularly pointed out that with the contactors constructed in the manner described, the circuit controller of itself can be of standard construction, and can be located on the ties where it is accessible and is not subjected to the direct vibration of the rails.

Associated with relay B is a buzzer BU the function of which will be made clear presently.

As shown in Fig. 1, all parts of the apparatus are in the positions which they occupy when no cars are to be retarded. That is to say, the contacts 72 of both contactors RC1 and RC2 are open, relay D occupies its deenergized position, the buzzer BU is deenergized, and lever L occupies its *p1* or "off" position in which all of the contacts with the exception of the contact 27-1 are open. Valve V2 is therefore deenergized, but valve V1 is energized over a circuit which passes from a suitable source of current here shown as a battery B through wires 75 and 76, back contact 77-77b of relay D, wire 78, contact 27-1 of lever L, line wire 33, wire 49, winding 20 of valve V1, and line wire 37 back to battery B. Since valve V1 is energized, cylinder 9 of motor M is connected with atmosphere through port 22, and the braking bars are therefore held in their non-braking positions by gravity. Furthermore, since cylinder 9 is vented to atmosphere, the contacts 26-26a of the pressure responsive devices P are all closed and the contacts 26-26b are all open.

If now with relay D in its deenergized position, lever L is moved to its *p2* position, the circuit previously traced for valve V1 will become interrupted so that this valve will become deenergized, and valve V2 will become energized over a circuit which passes from battery B through wires 75 and 76, back contact 77-77b of relay D, wires 78 and 32, contact 27-2 of lever L, line wire 38, contact 26-26a of pressure responsive device P20-30, wires 39, 40 and 50, winding 20 of valve V2, and line wire 37 back to battery B. The deenergization of valve V1 will cut off the supply of fluid pressure to cylinder 9 of motor M, while the energization of valve V2 will connect the cylinder with the pipe 24 so that fluid pressure will then be supplied to the cylinder thus moving the braking bars to their braking positions. When the pressure of the fluid in cylinder 9 increases to 20 pounds per square inch, contact

26-26a of pressure responsive device P20-30 will open and will deenergize valve V2, and if the pressure in the cylinder increases to 30 pounds per square inch, contact 26-26b of pressure responsive device P20-30 will become closed and will complete a circuit for valve V1, which circuit may be traced from battery B through wires 75 and 76, back contact 77-77b of relay D, wires 78 and 32, contact 27-2 of lever L, wire 38, contact 26-26b of pressure responsive device P20-30, wires 34 and 35, an asymmetric unit 51 in its low resistance direction, wire 49, winding 20 of valve V1, and line wire 37 back to battery B. Valve V1 will therefore become energized and will vent fluid from cylinder 9 to atmosphere until the pressure of the fluid in the cylinder increases sufficiently to cause contact 26-26b of pressure responsive device P20-30 to open and deenergize valve V1. It will be seen, therefore, that with the apparatus shown in Fig. 1, when lever L is moved to its *p2* position and relay D is deenergized, the braking bars will be held in their braking positions by a pressure of between 20 and 30 pounds per square inch.

If lever L is moved to its *p3* position when relay D is deenergized, valve V2 will become energized over a circuit which passes from battery B through wires 75 and 76, back contact 77-77b of relay D, wires 78, 32 and 31, contact 27-3 of lever L, wire 43, contact 26-26a of pressure responsive device P45-55, wires 40 and 50, winding 20 of valve V2, and line wire 37 back to battery B. Valve V2 will now remain energized until the pressure of the fluid in cylinder 9 increases to 45 pounds per square inch, at which time contact 26-26a of pressure responsive device P45-55 will open and will deenergize valve V2. If the pressure of the fluid in cylinder 9 increases to 55 pounds per square inch under these conditions, valve V1 will become energized over a circuit which passes from battery B through wires 75 and 76, back contact 77-77b of relay B, wires 78, 32 and 31, contact 27-3 of lever L, wire 43, contact 26-26b of pressure responsive device P45-55, wire 35, asymmetric unit 51 in its low resistance direction, wire 49, winding 20 of valve V1, and line wire 37 back to battery B. It will be seen, therefore, that when lever L occupies its *p3* position, the braking bars will be held in their braking positions by a pressure of between 45 and 55 pounds per square inch provided that relay D is then deenergized.

If lever L is moved to its *p4* position when relay D is deenergized, valve V2 will become energized and will remain energized until the pressure of the fluid in motor 9 increases to 70 pounds per square inch, the current for the valve under these conditions passing from battery B through wires 75 and 76, back contact 77-77b of relay D, wires 78, 32, 31 and 30, contact 27-4 of lever L, line wire 44, contact 26-26a of speed responsive device P70-80, wire 50, winding 20 of valve V2, and line wire 37 back to battery B. If the pressure of the fluid in the motor now increases to 80 pounds per square inch, valve V1 will become energized over a circuit which passes from battery B through wires 75 and 76, back contact 77-77b of relay D, wires 78, 32, 31 and 30, contact 27-4 of lever L, line wire 44, contact 26-26b of pressure responsive device P70-80, asymmetric unit 51 in its low resistance direction, wire 49, winding 20 of valve V1, and wire 37 back to battery B. It follows that when lever L occupies its *p4* position if relay D is then deenergized, the braking bars will be held in their braking

positions by a pressure of between 70 and 80 pounds per square inch.

If lever L is moved to its *p5* position when relay D is deenergized, valve V2 will become energized and will subsequently remain energized by virtue of a circuit which passes from a battery C through line wire 37, winding 20 of valve V2, an asymmetric unit 52 in its low resistance direction, line wire 44, contact 27-5 of lever L, wire 81, back contact 80 of relay D, and wire 79 back to battery C. Under these conditions, therefore, the braking bars will be held in their braking positions by a fluid at full line pressure.

It should be observed that if the operator moves the lever L from a position corresponding to a higher braking force to a position corresponding to a lower braking force, the apparatus immediately and automatically reduces the braking pressure to a value corresponding to the new position of the lever in a manner which will be apparent from the drawing without tracing the sequence of operation in detail.

When lever L occupies any one of its *p2*, *p3*, *p4*, or *p5* positions, so that the braking bars occupy their braking positions, and the operator wishes to restore the braking bars to their non-braking positions in which they are illustrated in the drawing, he will restore the lever L to its *p1* or "off" position. All circuits for valve V2 are then interrupted, and the circuit previously traced for valve V1 becomes closed at contact 27-1 of lever L. Valve V2 therefore becomes deenergized and cuts off the supply of fluid pressure to motor M, while valve V1 becomes energized and vents the fluid which was previously supplied to the motor to atmosphere. The braking bars therefore return to their braking positions under the influence of gravity. When the braking bars reach their braking positions, the parts are all restored to the positions in which they are illustrated in the drawing.

It should be pointed out that with the apparatus constructed as shown in Fig. 1, if the asymmetric unit 51 were omitted and the contacts of one of the pressure responsive devices became short circuited, as by a drop of water, when lever L occupies its *p1* or "off" position, the valves V1 and V2 would then both become energized, and there would be a continuous exhaust of fluid pressure from the source of atmosphere. The asymmetric unit 51, however, prevents this from happening because it prevents the flow of current from the line wire 33 to the pressure responsive devices, and hence to the valve V2, under these conditions. The asymmetric unit 52 is provided to permit selective control of the valves V1 and V2 over a single pair of line wires, by reversing the polarity of the current supplied to the line wires.

I shall now assume that lever L occupies any one of its *p2*, *p3*, *p4* or *p5* positions, so that the braking bars are in their braking positions, and that a locomotive having wide wheels approaches the retarder in the direction to pass the rail contactor RC1 prior to entering the retarder. As the locomotive passes the contactor RC1, the wide wheels of the locomotive will cause the associated contact 72 to become closed, and will thus complete a pick-up circuit for relay D which may be traced from battery B through wires 75 and 82, contact 72 of contactor RC1, wires 83, 84 and 85, the winding of relay D, and wire 86 back to battery B. Relay D will therefore pick up and will interrupt at its back contacts 77-77b and 80 all circuits previously traced for valve V2, and

will complete at its front contact 77-77a a circuit for valve V1 which circuit may be traced from battery B through wires 75 and 76, front contact 77-77a of relay D, wires 88, 33 and 49, 5 the winding of valve V1, and line wire 37 back to battery B. Valve V2 will therefore become deenergized and valve V1 will become energized thus causing the retarder to automatically move to its open or non-braking position. The contactor RC1 is positioned sufficiently far in advance of the retarder so that there is sufficient time for the retarder to open before a locomotive traveling at the ordinary yard speeds will reach the retarder, and it follows therefore that the locomotive will pass through the retarder without causing any damage.

When relay D becomes picked up in the manner just described it is subsequently held up by virtue of a stick circuit which may be traced from battery B through contact 27-2 to 5 of lever L, wire 89, front contact 87 of relay D, the winding of the buzzer BU, wires 90 and 85, the 20 winding of relay D, and wire 86 back to battery B. Since this stick circuit includes the buzzer BU, this buzzer will give an audible indication whenever the stick circuit is completed. It will be seen, therefore, that if a locomotive having wide wheels approaches the retarder when it is closed, the retarder will become automatically 25 opened and the buzzer will start to sound in the tower to thereby inform the operator that he has lost control of the retarder. The control of the retarder can be restored to the operator by simply returning the lever L to its "off" position. This movement of the lever will interrupt the 30 stick circuit for relay D at contact 27-2 to 5 of the lever, and as soon as the stick circuit becomes opened, relay D will become deenergized and will thus restore the apparatus to the position in 35 which it is shown in the drawing.

If a locomotive having wide wheels approaches the retarder in the direction to pass the contactor RC2 before it enters the retarder and the lever L then occupies any one of its "on" positions, the 40 resultant closing of the contact 72 of contactor RC2 will complete another pick-up circuit for relay D which will be obvious from an inspection of the drawing. Relay D will therefore become 45 picked up, and, when this happens, the apparatus will function to open the retarder in the same manner as was described above when relay D picked up due to a locomotive passing the contactor RC1.

Although I have herein shown and described 50 only one form of railway braking apparatus embodying my invention, it is understood that various changes and modifications may be made therein within the scope of the appended claims without departing from the spirit and scope of my invention.

Having thus described my invention, what I 55 claim is:

1. In combination, a car retarder, manually 60 operable means for opening and closing said car retarder, and means controlled by the wide wheels of a locomotive for opening said retarder if it is closed when the locomotive approaches it.

2. In combination, a car retarder provided with 65 a braking bar movable toward and away from a track rail to a braking and a non-braking position, manually operable means for controlling the movement of said braking bar to its braking and non-braking positions, and means for automatically moving said braking bar to its non-braking 70 position if it occupies its braking position when 75

a locomotive having wide wheels approaches it to prevent derailment of the locomotive or damage to the retarder by the locomotive or both.

3. In combination, a car retarder movable to open and closed positions, a manually operable lever having "on" and "off" positions, a relay, means for energizing said relay when a locomotive having wide wheels approaches said retarder, means effective if said relay becomes energized when said lever occupies its "on" position for subsequently maintaining it energized until said lever is moved to its "off" position, and means controlled jointly by said lever and said relay for controlling said retarder in such manner that said retarder will normally occupy its closed position when said lever occupies its "on" position but will be automatically moved to its open position if it occupies its closed position when said relay becomes energized.

4. In combination, a car retarder, a relay, means for energizing said relay when and only when a locomotive having wide wheels approaches said retarder, a manually operable lever, and means controlled jointly by said relay and said lever for controlling said retarder.

5. In combination, a car retarder, a manually operable lever located at a point remote from said retarder, a relay, means controlled by said lever for closing said retarder when and only when said relay is deenergized, means for energizing said relay when a car having wide wheels approaches said retarder, means for automatically opening said retarder if it is closed when said relay becomes energized, and means for indicating to the lever operator when said retarder becomes opened due to energization of said relay.

6. In combination, a car retarder having open and closed positions, a manually operable lever having an "off" and a plurality of "on" positions, a relay, means for energizing said relay when a locomotive having wide wheels approaches said retarder, a stick circuit for said relay including a contact of said lever closed in any of the "on" positions of the lever, an indication device included in said stick circuit for indicating to the lever operator when said stick circuit is closed, means for closing said retarder when said lever is moved to any one of its "on" positions if said relay is then deenergized and for opening said retarder when said lever is moved to its "off" position, and other means for opening said retarder if it is closed when said relay becomes energized.

7. In combination, a car retarder having open and closed positions, a manually operable lever having an "off" and an "on" position, two rail contactors one located in advance and one in rear of said retarder and each including a contact which becomes closed when and only when the wide wheels of a locomotive pass the contactor, means for energizing said relay when the contact of either contactor becomes closed, means for closing said retarder when said lever is moved to its "on" position provided said relay is then deenergized, means for opening said retarder if said relay becomes energized when said lever occupies its "on" position, and a stick circuit for said relay including a contact of said lever closed only in the "on" position of the lever.

8. In combination, a car retarder having open and closed positions, a manually operable lever having an "off" and an "on" position, two rail contactors one located in advance and one in rear of said retarder and each including a contact which becomes closed when and only when

the wide wheels of a locomotive pass the contactor, means for energizing said relay when the contact of either contactor becomes closed, means for closing said retarder when said lever is moved to its "on" position provided said relay is then deenergized, means for opening said retarder if said relay becomes energized when said lever occupies its "on" position, and a stick circuit for said relay including a contact of said lever closed only in the "on" position of the lever, said contactors being spaced sufficiently far from the retarder to give the retarder time to fully open before a locomotive traveling at ordinary yard speeds will reach the retarder after passing one of said contactors.

9. A trackway contactor for use with a track rail comprising a vertical lever provided at its upper end with a wheel engaging shoe and at its lower end with a recess which loosely receives the base flange of said rail in such manner that the lever is free to pivot about the base flange as a fulcrum, means for biasing said lever toward the rail, adjustable means for limiting the movement of the shoe toward the rail, and a circuit controller operatively connected with said lever.

10. A trackway contactor for use with a track rail comprising a vertical lever provided at its upper end with a wheel engaging shoe and at its lower end with a recess which loosely receives the base flange of said rail in such manner that the lever is free to pivot about the base flange as a fulcrum, means for biasing said lever toward the rail, adjustable means for limiting the movement of the shoe toward the rail, and a circuit controller operatively connected with said lever, said adjustable means being so adjusted that said lever will be rotated to operate said circuit controller when and only when a wide locomotive wheel passes said contactor.

11. In combination, a car retarder located in advance of a switch, a first contactor disposed in advance of said retarder, a second contactor disposed in rear of said retarder and having two operating arms one associated with both tracks leading from said switch, manually operable means for at times closing said retarder, and means controlled by said contactors for automatically opening said retarder when a locomotive having wide wheels passes either one of said contactors.

12. In combination, a car retarder, a track rail contactor operable only by a locomotive having wide wheels disposed in a position to be operated by a locomotive approaching said retarder, means for closing and opening said retarder, and means controlled by said contactor for automatically opening said retarder if said retarder is closed when said contactor becomes operated.

13. In combination, a manually operable lever having an "off" and an "on" position, a car retarder normally operable to an open or a closed position according as said lever occupies its "off" or an "on" position, and means effective if said retarder is closed when a locomotive having wide wheels approaches said retarder for automatically opening said retarder and for subsequently maintaining it open until said lever is moved from the "on" position it then occupies to its "off" position and back to an "on" position.

14. In combination, a manually operable lever having an "off" and an "on" position, a car retarder normally operable to an open or a closed position according as said lever occupies its "off" or an "on" position, a track rail contactor oper-

able only by a locomotive having wide wheels approaching said retarder, and means controlled by said contactor for automatically opening said retarder if it is closed when said contactor becomes operated.

15. In combination, a manually operable lever having an "off" and an "on" position, a car retarder normally operable to an open or a closed position according as said lever occupies its "off"

or an "on" position, a track rail contactor operable only by a locomotive having wide wheels approaching said retarder, and means controlled by said contactor for automatically opening said retarder if it is closed when said contactor becomes operated and for indicating to the lever operator that said retarder has been opened.
